UNITED STATES PATENT OFFICE.

ALBERT GERSTENDORFER AND MAX GERSTENDORFER, OF NEW YORK, N. Y.

DESIGN FOR AN ADVERTISING-COLUMN.

SPECIFICATION forming part of Design No. 28,618, dated May 10, 1898.

Application filed March 17, 1898. Serial No. 674,282. Term of patent 3½ years.

To all whom it may concern:

Be it known that we, ALBERT GERSTENDORFER and MAX GERSTENDORFER, citizens of the United States, and residents of the borough 5 of Manhattan, in the city, county, and State of New York, have invented and produced a new and original Design for an Advertising-Column, of which the following is a specification.

10 The leading feature of our design is an advertising-column substantially as shown in the accompanying drawing.

In the drawing, *a* is a base surmounted by a pillar *b*, the two integral portions *b'* *b''* thereof being of contrasting shades or colors. 15

What we claim is—

The design for an advertising-column, as shown and described.

ALBERT GERSTENDORFER.
MAX GERSTENDORFER.
